MOLD APPARATUS FOR CASTING METALS

Carl Wessel, Chicago, Ill.

Application June 21, 1945, Serial No. 600,719

8 Claims. (Cl. 22—152)

1

The present invention relates to mold apparatus for casting metals, and is particularly concerned with apparatus which constitutes a marked improvement over that disclosed in the prior patent to C. H. Bierbaum No. 1,138,443, Apparatus for producing castings, patented May 4, 1915.

One of the objects of the invention is the provision of a casting apparatus of the Bierbaum type, from which the disadvantages which are inherent in that and other prior art devices have been eliminated and which is adapted to produce castings of complex and intricate form, which are absolutely sound, nonporous, free from aggregations, impurities, or nonhomogeneous characteristics, and having an improved crystalline structure.

Another object of the invention is the provision of improved methods of making castings which are adapted to be of the character described, with a minimum of labor and with the expenditure of a minimum amount of time so that the castings may be produced in a quality and by what might be called mass production methods.

Another object of the invention is the provision of improved castings having homogeneous, sound body with improved crystalline structure and of various complex and intricate shapes that could not be made by any of the methods of the prior art.

Another object of the invention is the provision of apparatus and methods of casting which are so radically different in structure, operation, and method, and which are based upon the development and reconstruction of devices of the art prior to all of my previous inventions so that the present apparatus and methods have no relation or dependence, nor do they constitute improvements of my prior inventions.

Another object of the invention is the provision of improved apparatus and methods which are equally adaptable to use for all kinds of metals, and by means of which the perfect filling of the mold and the casting of substantially perfect counterparts of the pattern are practically assured for each operation so that there will be a minimum number of rejects.

Other objects and advantages of the invention will be apparent from the following description and the accompanying drawings, in which similar characters of reference indicate similar parts throughout the several views.

Referring to the drawings, of which there are three sheets,

Fig. 1 is a side elevational view of a casting

2

apparatus embodying my invention, certain parts of the apparatus being omitted from the right side of the drawing by reason of lack of space;

Fig. 2 is a top plan view of the apparatus, the mold being shown closed, in full lines, and open in dotted lines;

Fig. 3 is a fragmentary elevational view of the lower part of the machine of Fig. 1, which includes those elements that were omitted from Fig. 1 by reason of lack of space;

Fig. 4 is a view in perspective of the particular form of casting which may be made by means of the mold, which is included in the apparatus that has been chosen to illustrate the invention;

Fig. 5 is a view in perspective of the mold shown apart from the special form of ladle with which it is used;

Fig. 6 is a fragmentary top plan view showing the form of universal connection between the removable core and the threaded member that is used to withdraw or insert it;

Fig. 7 is a fragmentary vertical sectional view taken on the plane of the line 7—7 of Fig. 1, looking in the direction of the arrows, showing the structure of the mold in closed position and that part of the casting in the mold which appears at this plane;

Fig. 8 is a vertical sectional view, taken on a plane passing through the axis of the mold and the tilting ladle to which the mold is connected, showing the arrangement of the mold with respect to the supply of metal in the ladle prior to the formation of a casting.

Fig. 9 is a similar fragmentary view showing the position of the metal in the mold and ladle during the pouring of a casting;

Fig. 10 is a fragmentary sectional view showing the appearance of the casting in the mold after the pouring operation and after congelation, but before removal of the casting from the mold;

Figure 11 is a fragmentary view taken on the plane of the line 11—11 of Figure 9.

Referring to Figs. 1 and 2, 20 indicates in its entirety the casting apparatus, which includes a tilting ladle 21 and a suitable mold 22 directly connected to the ladle and having its filling opening registering with and communicating with the discharge opening of the ladle 21.

The ladle 21 is supported for tilting movement upon a frame 23, which may comprise a pair of similar standards 24 of the type shown in Fig. 1. These standards may be made of angle iron, which is assembled of a plurality of pieces, as shown, and welded together. For example, each standard 24 has an angle iron base 25, the hori-

zontal flange 26 of which engages the floor, and the vertical flange 27 of which is mitered to a suitable angle so that the juncture 28 between this flange and the similar flange on the upwardly extending frame members 29 and 30 may be welded together.

The upwardly extending frame members 29 and 30 preferably extend diagonally inward and upward from the ends of the base member 25, but are bent at 31 to extend vertically so that the upper parallel portions may be joined by a horizontal angle iron frame member 32, which is welded in place.

The two standards 24 which form the frame 23 are joined below the ladle 21 by angle irons 34, 35, the ends of which are welded to the upwardly extending frame members 29, 30 on each standard and by tie bolts 36 which bind the two frame members together by means of nuts 37.

Additional tie bolts 38 and braces 39 assure the absolute rigidity of the frame 23. The horizontal frame member 32 carries a vertically extending flange 40 which is provided with a horizontally extending bearing 41 for rotatably supporting the trunnions 42 of the ladle.

The trunnions 42 comprise stub shafts carried by the trunnion plate 43, which in turn is adjustably mounted by means of a plurality of screw bolts 44 on the channelled members 45, 46, which are secured to the ladle 21. The channelled members 45, 46 have their projecting flanges of suitable length and shape to engage the cylindrical shell 47 of the ladle 21 at the point at which these channels are located, so that they can be welded to the shell.

The channelled members 45, 46 are provided with a plurality of threaded bores 48 located at equally spaced points, so that the trunnion plate 43 may be shifted upward or downward to change the balance of the ladle 21, depending upon the amount of metal which is to be used or depending upon the weight, structure, and location of the mold.

Each trunnion 42 is preferably provided with a thrust bearing member 49 having a bore for fitting the trunnion and having a radially extending flange 50 for engaging the end of the bearing. The thrust collar 49 is secured in place by the set screw 51.

The ladle 21 preferably consists of a substantially cylindrical metal shell, the cylindrical portion of which is indicated by the numeral 52, this portion being welded to a heavier bottom plate 53 and to a top plate 54. The top plate 54 is provided at one side, such as the right side (Fig. 8) with a substantially rectangular slot 55, forming a filling aperture; and this aperture may be closed by means of a cover member 56 having a substantially flat upper body 57 and a cylindrical side flange 58, the cylindrical side flange being formed on a radius slightly larger than that of the side wall 52 so that it may overlap the side wall, which is also formed with a slot 59 at that corner communicating with the slot 55 to form a suitable aperture in the corner of the ladle shell.

The ladle is lined on its bottom, sides, and top with a heat resistant and heat insulating refractory lining 60 of substantial thickness, which is formed with a substantially cylindrical chamber 61.

The cylindrical side wall of the refractory lining is indicated at 62, the bottom wall 63 and the top wall 64. At the upper right corner (Fig. 8) where the metal shell has an opening, the refractory lining 64 also has an opening which

is defined by a pair of flat side walls 65, an upper wall 66 at the end of the lining top 64, and the horizontal wall 67 at the top of the side wall 62 of the refractory.

5 The angular cover 56 is filled with a block of refractory 68, which is triangular in cross section, and which is anchored to the cover 56 by suitable anchoring devices (not shown) and which overlaps the beveled surfaces 69 on the refractory lining 60 of the ladle surrounding the filling aperture.

10 The cover may be provided with any suitable form of handle 70, such as a large eye that can be engaged by a hook, and which is riveted in the wall 58 of the cover. The opposite edge of the cover plate 57 is formed with a hinge 71, which has a hinge plate 72 riveted or welded to the top plate 54 and is provided with a pintle 73.

15 Thus the cover provides a fairly tight closure for the chamber 61, but permits a limited amount of leakage; and it may be opened and laid over on the top plate 54 whenever it is desired to skim the metal in the ladle or to observe it or flux it or add to the charge.

20 The bottom wall 63 of the refractory lining 60 is formed with an upstanding pedestal 74 having a plane upper surface 75 which is of substantially the same size as the bottom 76 of the crucible 77, which is intended to be used in the ladle.

25 The crucible 77 may be made of any suitable refractory which is capable of withstanding the high temperatures to which the metal is to be subjected, and various compositions may be utilized for the crucible for the purpose of making sure that the metal is kept clean or for other effects upon the metal by the crucible.

30 Crucibles which may be purchased upon the open market may thus be embodied in the present ladle. The crucible 77 is smaller than the chamber 61, leaving an annular space 78 around the crucible for the projection of a heating flame.

35 At its upper edge the crucible 77 is preferably provided with an outwardly beveled surface 79 on its side, forming a sharp corner which may be anchored in the adjacent refractory 64 of the top wall, which closes the upper end of the crucible except for the following openings.

40 At the upper right corner a slot has been cut in the side wall 80 of the crucible, the bottom 50 of the slot being indicated at 81 and the sides at 82, this slot coinciding with the adjacent walls 65 and 67 of the opening in the refractory walls 64 and 62. This is the filling opening for the crucible, and the annular heating space 78 is 55 isolated from it by an auxiliary bottom wall 83 extending from the crucible to the side wall 62 and having its upper surface flush with the surfaces 81 and 67.

45 The member 83 may be a trough of substantially rectangular shape, the side wall of which extends upward and has its inner surfaces flush with the surfaces 65 and 82 on the refractory lining 62 and crucible 77.

50 This prevents any metal from falling down in 65 the annular space 78, but there is still an open space between the walls 65 above the trough member 83 so that the gases of combustion and flame in the space 78 may have access from that space to the opening 82 into the crucible 77 and 70 thence to the discharge opening and mold.

55 At the opposite side the crucible 77 is preferably formed with a round opening 84, which communicates with a short refractory conduit 85 of cylindrical shape that closes off the annular space 75 78 from this outlet.

The conduit 85 communicates with a cylindrical opening 86 in the refractory side wall 62 which leads to a registering opening of the same size in the shell wall 52. This is the discharge opening from the ladle leading to the mold, and it may be of various sizes and shapes; but it is preferably of generous size so that as the metal runs along its bottom into the mold the air or other gases may pass backward into the crucible chamber.

The metal shell 52 of the ladle is provided with an aperture registering with a bore 87 in the refractory wall 62 for receiving the burner nozzle 88, which is connected to suitable conduits 89 fastened by brackets to the ladle, and which are in connection with a flexible hose 90 leading to sources of air and combustible gas, such as illuminating gas, so that the burner may be operated while it is being tilted. The burner 88 projects the flame tangentially around the crucible. The burner nozzle 88 is smaller than the bore 87 so that additional air for combustion is drawn in through the bore 87, although the nozzle 88 is already supplied with air and combustible gas mixed in suitable proportion for efficient combustion. The gas and air are under a suitable compression as supplied to the nozzle 88 so that these elements are provided at suitable pressure and in suitable volume to provide a very hot flame which is projected into the space 78 surrounding the crucible 77, and which penetrates over into the crucible above the trough 83 and into the discharge openings 84, 85, 86. This provides a neutral atmosphere in the crucible chamber above the molten metal 91, and part of the gas of combustion escapes through the ladle discharge opening, which is left wide open, while the apparatus is being preheated by the flame, preliminary to its operation.

When it is being operated, the flame from the burner 88 may likewise be used to supplement the heat which is brought into the crucible by superheated batches of metal from a separate furnace to maintain the temperature of the metal 91 at a temperature near to the melting point so that casting may be accomplished under uniform temperature conditions.

In some embodiments of the invention the source of heat 88 may be a fuel oil burner of suitable construction, by means of which fuel oil is atomized and supplied with air at suitable pressure.

The metal shell 52 of the ladle is provided adjacent the discharge opening 86 with an enlarged opening 92, which also extends through a mold-supporting plate 93 so that the refractory may extend through these openings in the form of a collar into engagement with the mold plate 94, which supports the various parts of the mold as a unit.

The mold-supporting plate 93 may consist of a substantially rectangular plate that is secured directly against the side of the shell 52 and is braced and secured in place by means of angle irons 95, 96, which may be riveted or welded to the plate 93 and to the shell 52. The plate 93 has a plurality of through bores, which may be threaded to receive a plurality of screw bolts passing through bores in the plate 94 and threaded into plate 93 to secure the mold unit on the ladle unit, with the filling and discharge openings in registry.

Various types of molds may be attached to the ladle described for making castings of different shapes; but in general it is found that most molds require considerable development and

adaptation, and their construction must be peculiarly adapted for use with the present ladles in order to secure good results. The molds and all of the metal parts of the ladle previously described may be made out of steel, the molds in particular being made out of a mild steel which is suitable for this purpose on account of its working qualities.

However, in some embodiments of the invention sand molds, plaster of Paris molds, and any other types of molds known to the prior art may be employed; but if the molds are made of sand or plaster of Paris or other nondurable material, their parts are preferably supported in metal shells.

Referring to Fig. 4, this view shows in perspective a casting 100, which may be made by means of the present apparatus. It consists of a substantially cylindrical body 101 having a centrally located cylindrical stem 102 extending from its closed end.

The body 101 is hollow, having a relatively large concentric bore 103, and it is provided with a pair of substantially circular ports 104, 105 located in the body wall 101 diametrically opposite to each other. The ports 104, 105 are each provided with one or more transversely located curved bars 106, 107, the bars being of substantially rectangular cross section and of the same thickness as the wall 108 of the body and provided with outer surfaces which are partially cylindrical and formed by elements of the same cylinder forming the body 101.

The bore 103 has a slight taper so as to permit the withdrawal of the core 109 by means of which this bore is formed.

Referring now to Fig. 5, the main parts of the mold comprise the supporting plate 94, the two mold halves 110 and 111, the central core 109, and a pair of side cores 112, 113.

Each of the mold halves 110, 111 may consist of a block of metal, such as steel, having plane rectangular sides, one of these sides being formed with a half of the mold cavity. Each block 110, 111 is preferably built up of a plurality of sections or smaller blocks which are secured together and held in alignment by steel dowel pins in accurately located bores.

The cavities formed in the two blocks may be identical, as the present casting is symmetrical; and each cavity may comprise one-half of the cavity necessary to form the complete article.

In the present casting the mold is provided with a frusto-conical or funnel-shaped filling opening 114 leading to a cylindrical bore 115, which forms the stem 102. The cylindrical bore 115 communicates with the enlarged bore 116, which forms the cylindrical body 101 of the casting; and the bore 116 communicates with a smaller bore 117 for receiving and guiding the central core 109, to which bore 117 is substantially complementary.

Thus each of the mold halves 110, 111 is formed with a cavity capable of providing the space for one-half of the bores 114 to 117, these half cavities registering with each other when the mold is closed.

In addition to this, each mold block 110, 111 is provided with a through bore 118, the bores being located to receive the cores 112, 113 (Fig. 7) which form the circular apertures 105 and form the partially cylindrical bars 106, 107 of the casting.

The side cores 112, 113 each comprise a substantially cylindrical body which is provided with

a cylindrical enlargement 119, the cylindrical enlargement having a thrust surface 120 which engages the side of each mold block to limit the inward movement of the cores 112, 113.

The cores 112, 113 are provided with a partially cylindrical inner surface 121 which engages the central core 109 and is complementary thereto, for forming the circular apertures 104, 105; but this cylindrical surface 121 is formed with a pair of transverse rectangular grooves open at each end to communicate with the space for the side wall 108 so as to form the transverse bars 106, 107 of the casting.

It is necessary that such cores as the side cores 112, 113 be definitely held in a proper rotative position; and therefore each head 119 is provided with a pair of dowel pins, such as, for example, dowel pin 122, which is received in a short socket 123 in each block, and also the dowel pin 124 which may be secured in the socket 125 in each mold block, but may slide in an aperture 126 in the cylindrical member 119 of each core 112, 113.

The cores 112, 113 are preferably provided with a form of force multiplying means for retracting them; but, as these cores are not located deeply in the casting, it is sufficient to provide a bellcrank lever 127, the longer arm 128 of which serves as a handle, and the short arm 129 of which has a bore for receiving a screw bolt 130 which is threaded into the head 119 of each core.

The bellcranks 127 are each pivoted on a suitable bracket 131 carried by the mold block so that a pull on the handle 128 is sufficient to retract the cores 112, 113 from the apertures 104, 105 of the casting. The central core 109 is likewise preferably provided with a cylindrical head 131, having an annular thrust surface 132, which engages the plane end 133 of the mold assembly, to determine the position of the core 109 in the assembly and to make the end wall of the casting of definite thickness.

This core is also provided with force multiplying means for retracting it, which is preferably in the form of a screw shaft 133, which is carried by a threaded bore 134 located in a supporting plate 135.

The core 109 and its operating mechanism are preferably permanently attached to the block 110 so as to move with it; and for this purpose the block 110 may have a pair of cross bars 136, 137 bolted or welded to it. The cross bars 136 support at their ends four bolts 138, which may be surrounded by tubular spacers so that when the bolts are threaded home in the bars 136, 137 the tubular spacers space the plate 135 from the bars 136 and hold it parallel to the end surface 133 of the mold assembly.

Referring to Fig. 6, the screw shaft 133 is preferably provided with a reduced threaded end portion 139 that passes through an enlarged bore 140 in a partially spherical cup 141. The reduced threaded portion 139 is provided with a nut and lock nut 142, which are located with a clearance with respect to the annular shoulder 143 so that there is a limited universal joint between the screw shaft 133 and the cup 141.

The cup 141 is fixedly secured by means of a plurality of screw bolts 144 to the head 131 of the central core, the bolts passing through the attaching flange of the cup and being threaded into the head so that the core 109 may have a limited universal movement; and as seen in Fig. 5 the core 109 has moved out of the half bore 117.

When the mold halves are assembled, however,

the core 109 has a sliding fit in the bore 117. At its left end the screw shaft 133 carries a cross bar 145, serving as a handle for rotating the shaft 133. The handle 145 is secured in a slot 5 in the shaft 133 by the screw bolt 146. The two mold halves 110, 111 comprise block assemblies of equal length, each of which is provided with a plane end surface 147. When the mold is closed, these plane end surfaces 147 are in the same 10 plane, and the funnel-shaped opening 114 registers with the opening 148 in the plate 93 and with the opening 149 in the plate 94.

It is necessary for these mold halves to move in a particular manner to separate the mold 15 from the casting and to separate the casting from the machine. For this purpose the plate 94 is provided with a pair of guide bars 150 and 151 mounted in parallel position on the plate 94 by means of a plurality of screw bolts or rivets 152 which pass through spacers 153 so that the mold halves 110, 111 may be guided at a point spaced from the plate 94.

The guide bars 150, 151 (Fig. 7) are provided with opposed slots 154, preferably rectangular 25 in cross section and adapted to receive the upwardly and outwardly projecting reduced portions 155 of an actuating bar 156, which is carried by the right side of the mold half 111.

The actuating bar 156 consists of a rectangular 30 bar having six plane sides, the end surfaces of which slidably engage the opposed plane surfaces on the guide bars 150, 151. The reduced portions 155 of the actuating bar 156 are slidably mounted in the rectangular slots 154 in the guide bars 150, 35 151. At the same time the plane end 147 of the mold half 111 slidably engages the outer surface of the plate 94.

Thus the mold half 111 is mounted for sliding movement away from the point of registry with 40 the opening 149 in the plate 94, but the end of the slot 154 acts as a stop for positioning this mold half in registry with half of the opening 149.

In order to move the mold half 111, it is preferably provided with an outwardly projecting connecting rod 157, which may consist of a rectangular bar fixedly secured by a rivet in a complementary slot in the actuating bar 156. The end of the connecting rod 157 is slotted and provided with registering bores for the pintle 158, which 50 also passes through the hole in the handle lever 159.

The handle lever 159 is elongated at its upper end sufficiently to provide a force multiplying action, and is shaped with a handle 160 at its 55 upper end. At its lower end it is pivotally secured by means of a rivet 161 to a laterally projecting bar 162, which is fixedly secured to the plate 94 by a pair of rivets.

In order to compensate for the fixity of the connecting rod 157 in the actuating bar 156 the lever 60 159 has a slot 163 for the pintle 158. Thus a pull on the lever 159 is adapted to cause the mold half 111 to draw away from the casting in the mold from the full line position of Fig. 7 to the dotted 65 line position in this view.

For the support of the other mold half 110 the guide bars 150 are provided with a pair of spacers 153 at the left end of each guide bar 150, 151, and the aperture 164 between these spacers is 70 adapted to receive the reduced cylindrical end 165 of the actuating bar 166 for the mold half 110.

The actuating bar 166 is fixedly secured to the mold half 110 by rivets, bolts, or other fastening means, and this bar is provided with a partially 75 cylindrical portion 167, which is curved on a

radius equal to the distance of the trunnion 165 from the plate 94 when the mold is assembled as shown in Fig. 10.

The slot 164 is larger than the trunnion 165 in order to provide a clearance at this point so that the mold halves 110, 111 may be clamped together tightly with their inner plane surfaces 168 engaging each other and so that they will not be restricted by the trunnions 165. In order to assure the alignment of the two mold halves the mold half 111 is provided with a plurality of cylindrical bores 169 in its face 168 and the opposite mold half 110 is provided with projecting dowels 170 engaging in the bores 169 and effecting a positive alignment of the mold halves.

In order to clamp the mold halves together, mold member 111 may be provided at its plane top and bottom surfaces 171, 172 with upwardly and downwardly projecting pins 173. The other mold half 110 may be provided with a pivoted lever 174 mounted upon a pin 175 and provided with a hook 176 having a curved camming surface 177. The lever 174 may be actuated by an upwardly extending handle 178; and when the mold halves are assembled, the camming surface 177 may be pushed over the pin 173 to draw the molds tightly together.

Referring now to Fig. 3, the tilting ladle 21 is preferably provided with a laterally projecting bifurcated arm 180, the legs of which are located on the opposite sides of a connecting rod 181. The connecting rod 181 carries a piston 182, which is slidably mounted in a cylinder 183.

The cylinder 183 is fixedly mounted upon an extension 184 of the base member 25, and is provided with a conduit 185 having a throttling valve 186, the conduit leading to the lower end of the cylinder.

The piston 182 is a one way piston having an upwardly extending cup leather 187 carried by a suitable cylindrical member 188 and having a beveled edge 189 so that upon the upward movement of the piston air is sucked into the base of the cylinder 183, but upon the connecting rod being relieved of any thrust the piston and rod drop again by gravity.

The connecting rod 181 is preferably cylindrical, and the piston preferably has an upwardly extending frame 190 provided with a centrally located guide member 191 having a bore 192 for guiding the rod 181 so that the rod 181 projects upward in a vertical direction.

The guide member 191 may be an elongated threaded member threaded into a bore 193 in the frame 190 so as to serve as an adjustable stop for determining the maximum amount of tilt of the ladle 21 in a counterclockwise direction in Fig. 3. At its upper end the piston rod 181 is provided with a multiplicity of apertures 194 for receiving a through bolt 195 carrying a roller 196 on each side of the connecting rod 183 for engaging the two legs of the ladle-carried arm 180.

Below the arm 180, when the piston 182 is in its lowermost position, and the ladle 21 is level, the connecting rod 181 is provided with additional apertures 194 for receiving another through bolt 197 provided with similar rollers 198 for engaging the lower side of the arms 180.

Thus the piston 182, rod 181, and lower rollers 198 serve as a stop to determine the range of movement of the ladle in a clockwise direction in Fig. 3 so as to make sure that the ladle will not tilt toward the right far enough for the metal to spill out of the aperture 67.

The rollers 198 also serve to insure the quick

return of the piston to its lowermost position for the next casting operation. The multiplicity of apertures 194 serve to permit adjustment of the positions of the rollers 196 and 198 so that on the tilting of the ladle 21 the piston 182 does not come into play until the mold has tilted to a predetermined position, after which the piston and cylinder serve as a jack pot in absorbing the shock of the tilting motion of the ladle and bringing the ladle to a stop, and they serve also to place a predetermined suction on predetermined parts of the mold at the proper time to remove the air from the mold and to permit a perfect filling of the mold by metal.

The suction pipe 185 is connected through valve 186 to a flexible conduit or hose 199, which may be armored or otherwise protected from the heat; and the hose is provided with a metal fitting 200 (Fig. 1), which is threaded into the upper face 201 of one of the mold sections, such as the mold section 111 (Fig. 1; Fig. 7).

The fitting 200 extends into a threaded bore 204, which may communicate with a longitudinally extending bore 202, which is closed at each end, but which otherwise extends substantially through all of the sections or blocks of which each mold half is made.

Referring to Fig. 5, it will be seen that the mold member 110 is made of four sections, indicated at 203, 204, 205, 206. These sections are indicated by the lines of division 207, 208, 209.

Referring now to Fig. 11, this is a fragmentary view, showing one of the faces of one of these sections 203-206, taken on the plane of the line 11-11 of Fig. 9. This is exemplary of all of the faces of the various sections which are in contact with each other. Each of such section faces is provided with a partially circular groove conduit 210, which is preferably formed on the line of a circle so that it may be cut in the block by means of a lathe.

The conduit 210 may be of any suitable size to carry sufficient air, but is a relatively small conduit communicating with the conduit 202 leading to the hose 199, and has all of the similar circular conduits 210 in the various faces of the mold half sections communicating with the same bore 202. It will be evident that the mold has suitable circular conduits between each of the mold sections communicating with a source of suction.

The faces of the mold sections at the junctures 207, 208, and 209 are also formed with a multiplicity of radially extending fine grooves 211. These grooves may be located on one or both of the contacting faces, but the grooves 211 are sufficiently small so that while they will pass air, they will not pass the molten metal of which the casting is being made.

Thus all of the corners of the mold cavity are connected by means of these fine grooves 211 with suitable suction conduits leading back to the suction cylinder 183 so that by means of suitable adjustments suction can be applied to any or all parts of the mold where air may be entrapped.

The operation of the apparatus is substantially as follows: The mold is assembled with the ladle and placed in the open position, as shown in Fig. 5; and the crucible 77 of the ladle is first preheated by means of the burner 88, the gases of combustion passing around the crucible and up into the filling trough 83 and into the crucible and out of the discharge apertures 84, 85, 86 past the mold, which is also slightly preheated.

However, I prefer not to rely upon the flame

for preheating the mold, but the preheating of the mold may be done by making a few castings, such as five or ten castings, preferably the latter, which castings are rejected, and melted upon the beginning of operations.

After the ladle has been preheated for a suitable length of time, the door 56 may be opened and a charge of metal may be poured into the crucible 77, this metal having been previously melted in a separate furnace; and the ladle is preferably provided with sufficient metal to make a multiplicity of castings. The temperature of the metal in the crucible of the ladle is maintained by continuing the operation of the flame from the burner 88 and also by supplying the ladle with additional batches of molten metal, which are superheated above the desired temperature so as to raise the temperature of the metal in the ladle crucible and maintain it at the temperature desired. The metal in the crucible of the ladle is fluxed, if necessary, and carefully skimmed to make sure that it is absolutely clean and homogeneous and when it is in proper condition, from the point of view of cleanliness, temperature, etc., the casting operations may be begun.

The temperature at which casting is carried on is preferably quite close to the melting temperature for the metal which is being used, so that the casting may congeal quite quickly, and thus operations can be speeded up without delaying for the congealing and cooling of the castings.

The mold should first be closed and the two mold halves secured together by means of the hooks 174. In order to do this, it is necessary to swing the mold half 110 around toward the observer in Fig. 5 until the face 147 strikes the outer surface of the plate 94. Then the mold half 111 may be caused to slide on the guide bars 150, 151 by means of the handle 160, which is pushed inward until the actuating bar 155 reaches the end of the slots 154, where this mold half is in registry with the discharge opening of the ladle.

The two mold halves are then secured together by means of the hooks 174, which cam the two halves of the mold tightly together and secure them. The position of the trunnion 165 on the mold half 110 is such that the bars 150, 151 hold this mold half tightly against the plate 94 by engagement of the bars 150, 151 with the trunnions 165 when this mold half 110 is in the position at right angles to the plate 94.

Although the mass production of castings involves the melting of metal in a furnace other than the ladle which supports the mold, for small operations or for experimental operations involving the adjustment, correction, or adaptation of the mold, the metal may be melted in the crucible by the flame which is projected tangentially around the crucible.

The side cores 112, 113 should then be shoved into place by moving the bellcranks 121 in the proper direction to move these cores into the mold. The central core 109 should then be driven in by turning the screw shaft 133 in a clockwise direction by means of the handle 145 until the annular surface 132 strikes the outer face of the mold assembly. This leaves the core 109 spaced sufficiently from the end of the mold cavity to form the end wall of the casting 100.

The dowel pins 170 in their sockets 169 will insure the two halves of the mold being in absolute registry. The side cores 112, 113 should

engage the central core 109 with those complementary end portions of the surfaces of the side cores which remain on either side of the grooves.

The machine is then in condition to start the making of a casting; and Figs. 8 and 9 illustrate the action of the apparatus at this time. In Fig. 8 it will be seen that the free surface of the molten metal 91 in the crucible 77 is below the discharge apertures 84, 86. The operator may then tilt the ladle by means of a suitable handle 212, the tilting action being in a counterclockwise direction in Fig. 8.

This causes the free surface of the molten metal to rise above the lowest part of the discharge aperture 84; and without splashing or agitation the molten metal will run down hill in the discharge aperture 86 into the mold cavity to the lowermost part of the mold cavity. The tilting motion should take place slowly and at a constantly increasing angle of tilt so that the molten metal flows continuously down hill into the mold cavity, which is filled without any splashing or separation into drops or segregation of any parts of metal which must be again remelted.

As the mold cavity fills from the bottom upward, the discharge aperture into the ladle is large enough so that the air from the mold cavity may pass back into the ladle above the free surface of the metal over the major portion of the filling operation of the mold. During this time that portion of the mold which is first filled begins to congeal first, but metal is constantly added above the congealing and most remote part of the mold, and the congealing progresses gradually upward from the bottom of the mold cavity toward the top and back to the metal in the ladle.

The present casting is merely exemplary of one form of casting which may have one or more uppermost portions of its cavity from which the air should be exhausted, such as, for example, the point 213 in the upper corner of the casting 100 (Fig. 4; Fig. 9). At a certain point in the filling of the mold the free surface of the metal in the mold and ladle will rise until it cuts off at the corner 214 (Fig. 9) the return of air from the mold to the ladle.

Just prior to this point the suction action of the piston 182 and cylinder 183 comes into play and the upper roller 196 on the connecting rod 181 is suitably adjusted to be engaged by the arm 180 at such a time. Thus before the air is cut off from returning to the ladle, the piston and cylinder 182, 183 begin action and place a suction on the minute groove conduits 211 in the faces of the sections of which the mold halves are constructed.

As certain of these grooves 211 are located to extend radially from the corner 213 in the mold cavity (Fig. 9), the air above the metal in this particular corner is no longer entrapped, but is gradually removed without any agitation or parts of the air being honey-combed into the casting.

The action of the source of suction is so co-ordinated with the flow of the metal into the mold from the ladle that the air is simply removed and the mold cavity is completely filled, and thereafter the filling continues by the molten metal running down hill into the cavity until it has filled that portion of the mold cavity that forms the stem 102 and extends into the funnel-shaped opening 114, as shown in Fig. 10.

At this time the mold has been completely filled and, during its filling, congealing has been

going on until the congealation extends backward into the funnel-shaped opening 114, the free surface of the congealed portion being indicated at 215 (Fig. 10). At this time the piston 182 has reached its upper limit of movement, which is determined by adjustment of the threaded stop member 191 that also guides the piston rod 181, and further tilting motion is arrested.

The air piston not only removes the air from the mold, but it acts like a dash pot to effectively cushion the end of the tilting of the mold so that there is a minimum amount of a tendency for the metal to be disturbed in the ladle.

The time required for tilting the mold is a matter to be determined by trial, and this time should be made as short as possible to expedite the making of castings; but it should be long enough so that the mold is filled by the continuous pouring without splashing and with a continuous filling of the mold from the bottom upward to the filling opening.

In some cases it may be necessary to hold the ladle in the tilted position for a short time to give the casting time to congeal properly. This may also be determined by trial and by observation, and by the amount of sprue that is left on the casting after the machine has been tilted back to the vertical position.

Assuming that the casting has congealed to the point 215, shown in Fig. 10, the machine is then tilted back to the vertical position, this motion being limited by the lower roller 198, which also serves to return the piston to its lowermost position, aided by gravity and by the fact that the piston is a one way piston, producing suction only on the upward stroke.

Then the operator should immediately remove the cores, such as, for example, the central core 109, by screwing the screw shaft 133 in a counter-clockwise direction until the core 109 reaches the position of Fig. 5. The two side cores 112, 113 should be withdrawn by rotating the bellcranks 127 in such direction as to pull these cores outward.

Then the hooks 174 should be unhooked and moved to the position of Fig. 5 to release the mold halves from being held together. As the casting is intended to move with the mold half 110, the mold half 111 should first be separated from the casting by drawing outward on the handle 160, which causes this mold half to slide away from the casting.

This sliding motion is sufficient to move the mold half 111 far enough away so that this mold half does not interfere with the pivotal movement of the casting as it is held in the mold half 110.

The casting is held in the mold half 110 because the sprue, which may have parts of its wall extending into engagement with the plate 94, tends to hold the casting in the position in which it was cast. Thus the handle 160, which slides the mold half 111 to the right in Fig. 5, leaves the casting with its sprue communicating with the filling opening and its body in the mold half 110. When the mold half 110 is pivoted clockwise, looking from the top in Fig. 5, the location of handle 145 and length of the mold assembly is such that there is considerable leverage exerted about the pivot 164. This leverage will enable the operator to pull the sprue loose from the filling opening, the casting going with the mold half 110 in its pivotal movement. The handle 145 may then serve as a handle for causing the mold half 110 to pivot in a clockwise direction, looking at the top of Fig. 5, to draw the casting away from

the plate 94, the casting being in the half cavity of the mold half 110. The casting may then be grasped, so that it is promptly removed from the half cavity in the mold half 110, which is preferably done by grasping it with tongs or other tools adjacent the exposed portion of the sprue formation so that there is no danger of marring any other part of the casting.

In order to assure the easy removal of the casting, the sprue should be kept within the funnel-shaped portion 114 of the mold, but the conduit leading from this funnel-shaped portion into the ladle may be tapered inwardly so that if the sprue should be longer it will, nevertheless, be easily removable with the casting, due to this taper.

The slideable mounting for the pivoted members 165 on the mold half 110 also facilitates the easy removal of the casting from its position of Fig. 10 to that of Fig. 5. The mold should then be closed at once and the cores put in proper place, and all parts properly secured, ready for the making of another casting.

The method of making castings with the present apparatus is briefly outlined as follows:

In order to assure a high degree of uniformity between the castings, the supply of metal should be kept uniform, and I propose to use a multiplicity of casting machines of the type shown in connection with a single very large furnace, from which the batches of metal will be periodically taken in a molten condition. As batches are taken out of the large furnace, additional metal will be added, which will, however, be small in proportion to the total mass of molten metal, and will not vary its composition greatly.

The batches of superheated metal placed in the crucible of the present casting apparatus will tend to maintain the proper temperature for casting, and this may be supplemented by means of the flame, which keeps the apparatus at proper temperature.

In the making of a casting according to the present invention the use of any pressure whatever is preferably totally eliminated. I find it is not necessary to use any hydrostatic head of metal on top of the metal in the casting by means of the metal in the ladle, as it is not necessary to tilt the machine to this extent.

The machine need only be tilted sufficiently to cause the metal to flow through the bottom part of the discharge opening, leaving the major portion of this opening free for the return of air. Then the metal runs down into the mold, filling it from the bottom, which is, of course, most remote from the filling opening of the mold; and as the mold is filled, there is always a portion of molten metal at the top of the metal in the mold, but the metal already deposited in the mold begins to be chilled and starts to congeal from the bottom up as it is being filled.

Thus any shrinkage is automatically taken up by the fact that metal is being supplied from the top during the congealing.

The use of suction at a predetermined point during the tilting action does not involve the application of any pressure to the metal, but rather involves merely the removal of the air that may otherwise be entrapped in certain parts of the mold after filling has proceeded to a point where molten metal is filling up in the filling opening.

Where air is entrapped in a mold and pressure is applied, as in ordinary die casting methods and many of the methods of the prior art, there is a

tendency for the air to be forced into the metal in the form of bubbles and foam, producing a porous condition which may not be discernible from the outside of the casting.

This is totally eliminated by my method, which involves the removal of the air from the mold by a moderate suction at a proper time. The suction, which may also be applied to other parts of the mold that are already filled, produces no effect.

When it is necessary to pour a casting in such a way that two branches or parts which separate are being filled, the mold is preferably arranged so that the metal will run down into both of them; and if these branches are again to join, it is so arranged that when, during the course of filling, these two branches of the casting join, they will both be in the molten condition so that a perfect molten junction will be formed.

During all of this time a neutral atmosphere is maintained above the metal in the ladle and leading to the mold by the flame, which has access to the space above the metal and to the mold cavity, and the products of combustion from this flame leak out through the cracks between the halves of the mold and through the cracks around the cover opening for the ladle.

A slight increased pressure is maintained in the ladle over that outside by this action, so that air is excluded.

The casting apparatus embodying the present invention occupies a very small space when compared with the casting apparatus of the prior art for accomplishing the same purpose. It permits the use of a minimum amount of labor, and several hundred castings may be produced with a single machine having a mold with a single cavity in the course of a working day by one or two men.

The mold should, of course, be constantly kept in a clean condition, and with some metals it may be necessary to spray the inner surface of the mold with a separation compound, but with other metals it is not at all necessary.

The present apparatus may be constructed at a very low cost; and although molds made of steel are more expensive, the cost is readily absorbed in the cost of the many castings that can be made without deterioration of such a mold. As previously stated, any type of mold may be used with my apparatus and method, and the present mold is merely exemplary of one type of mold for carrying out the method.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A mold for the casting of metals, comprising a supporting plate, said supporting plate having a filling aperture and a pair of mold members, each having substantially half of the cavity formed in it, one mold member being provided with a plane end surface engaging said plate, and with guide means for slidably supporting said mold member for sliding movement on said plate, away from the filling opening, the other mold member being mounted for pivotal movement on said plate in a direction away from the adjacent mold member whereby, after the casting has congealed, one mold member may be slid away from the casting and the other mold member may be

pivoted outwardly, carrying the casting with it, away from the supporting plate, and a supporting frame carried by said other mold member and having a threaded bore and an axially extending core carried by a screw shaft in said bore and extending into a bore which forms a part of the cavity in said mold to form a tubular casting.

2. A mold for the casting of metals, comprising a supporting plate, said supporting plate having a filling aperture and a pair of mold members, each having substantially half of the cavity formed in it, one mold member being provided with a plane end surface engaging said plate, and with guide means for slidably supporting said mold member for sliding movement on said plate, away from the filling opening, the other mold member being mounted for pivotal movement on said plate in a direction away from the adjacent mold member whereby, after the casting has congealed, one mold member may be slid away from the casting and the other mold member may be pivoted outwardly, carrying the casting with it, away from the supporting plate, and a supporting frame carried by said other mold member and having a threaded bore and an axially extending core carried by a screw shaft in said bore and extending into a bore which forms a part of the cavity in said mold to form a tubular casting, each of said mold halves being provided with a transversely extending bore and a sliding core in each of said transverse bores, said sliding cores being formed with partially cylindrical end surfaces engaging the first-mentioned axially extending core for forming apertures in the sides of said tubular member.

3. A mold for making a casting having a sprue, comprising a supporting plate provided with a filling opening of sufficient size to pass molten metal into the mold while the gases in the mold are passing out of the mold above the molten metal through said opening, and a pair of mold members movably mounted upon said supporting plate, each of said movable members being a metal member having a part of a mold cavity formed in it, one of said mold members being mounted for pivotal movement on the plate, and the other of said members being mounted for sliding movement on said plate, away from the first-mentioned mold member, whereby one half of the mold may be slid transversely on said plate to expose that portion of the casting that is formed by said half mold member, after which the casting and other mold member may be pivoted away from the plate to draw the sprue away from the filling opening of the plate, and securing means for holding said mold members together when they are engaging each other and engaging said plate, said mold members each being formed with a partially cylindrical groove providing a cylindrical bore when they are joined, and said bore having a slidable metal core located therein to form the casting with a bore in its end opposite to the filling opening, the said core being substantially cylindrical, and the mold members each being formed with an enlarged counterbore into which said core projects, and the core stopping short of the end of said counterbore, whereby the mold members and core form a cavity for a cylindrical cup-shaped member, and threaded means for withdrawing said core from the mold.

4. A mold for making a casting having a sprue, comprising a supporting plate provided with a filling opening of sufficient size to pass molten metal into the mold while the gases in the mold

are passing out of the mold above the molten metal through said opening, and a pair of mold members movably mounted upon said supporting plate, each of said movable members being a metal member having a part of a mold cavity formed in it, one of said mold members being mounted for pivotal movement on the plate, and the other of said members being mounted for sliding movement on said plate, away from the first-mentioned mold member, whereby one half of the mold may be slid transversely on said plate to expose that portion of the casting that is formed by said half mold member, after which the casting and other mold member may be pivoted away from the plate to draw the sprue away from the filling opening of the plate, and securing means for holding said mold members together when they are engaging each other and engaging said plate, said mold members each being formed with a partially cylindrical groove providing a cylindrical bore when they are joined, and said bore having a slidable metal core located therein to form the casting with a bore in its end opposite to the filling opening, the said core being substantially cylindrical, and the mold members each being formed with an enlarged counterbore into which said core projects, and the core stopping short of the end of said counterbore, whereby the mold members and core form a cavity for a cylindrical cup-shaped member, and threaded means for withdrawing said core from the mold, said mold being provided with a cross head and a threaded member for engaging said threaded means.

5. A mold for making a casting having a sprue, comprising a supporting plate provided with a filling opening of sufficient size to pass molten metal into the mold while the gases in the mold are passing out of the mold above the molten metal through said opening, and a pair of mold members movably mounted upon said supporting plate, each of said movable members being a metal member having a part of a mold cavity formed in it, one of said mold members being mounted for pivotal movement on the plate, and the other of said members being mounted for sliding movement on said plate, away from the first-mentioned mold member, whereby one half of the mold may be slid transversely on said plate to expose that portion of the casting that is formed by said half mold member, after which the casting and other mold member may be pivoted away from the plate to draw the sprue away from the filling opening of the plate, and securing means for holding said mold members together when they are engaging each other and engaging said plate, said mold members each being formed with a partially cylindrical groove providing a cylindrical bore when they are joined, and said bore having a slidable metal core located therein to form the casting with a bore in its end opposite to the filling opening, the said core being substantially cylindrical, and the mold members each being formed with an enlarged counterbore into which said core projects, and the core stopping short of the end of said counterbore, whereby the mold members and core form a cavity for a cylindrical cup-shaped member, and threaded means for withdrawing said core from the mold, said mold being provided with a cross head and a threaded member for engaging said threaded means, said threaded means having a limited universal connection to the end of said core.

6. A mold for making a casting having a sprue,

comprising a supporting plate provided with a filling opening of sufficient size to pass molten metal into the mold while the gases in the mold are passing out of the mold above the molten metal through said opening, and a pair of mold members movably mounted upon said supporting plate, each of said movable members being a metal member having a part of a mold cavity formed in it, one of said mold members being mounted for pivotal movement on the plate, and the other of said members being mounted for sliding movement on said plate, away from the first-mentioned mold member, whereby one half of the mold may be slid transversely on said plate to expose that portion of the casting that is formed by said half mold member, after which the casting and other mold member may be pivoted away from the plate to draw the sprue away from the filling opening of the plate, and securing means for holding said mold members together when they are engaging each other and engaging said plate, said mold members each being formed with a partially cylindrical groove providing a cylindrical bore when they are joined, and said bore having a slidable metal core located therein to form the casting with a bore in its end opposite to the filling opening, the said core being substantially cylindrical, and the mold members each being formed with an enlarged counterbore into which said core projects, and the core stopping short of the end of said counterbore, whereby the mold members and core form a cavity for a cylindrical cup-shaped member, one of said mold members being formed with a transversely extending bore, and a core mounted in said latter bore and movable into engagement with the first-mentioned core to form the cup-shaped casting, with a lateral aperture.

7. A mold for making a casting having a sprue, comprising a supporting plate provided with a filling opening of sufficient size to pass molten metal into the mold while the gases in the mold are passing out of the mold above the molten metal through said opening, and a pair of mold members movably mounted upon said supporting plate, each of said movable members being a metal member having a part of a mold cavity formed in it, one of said mold members being mounted for pivotal movement on the plate, and the other of said members being mounted for sliding movement on said plate, away from the first-mentioned mold member, whereby one half of the mold may be slid transversely on said plate to expose that portion of the casting that is formed by said half mold member, after which the casting and other mold member may be pivoted away from the plate to draw the sprue away from the filling opening of the plate, and securing means for holding said mold members together when they are engaging each other and engaging said plate, said mold members each being formed with a partially cylindrical groove providing a cylindrical bore when they are joined, and said bore having a slidable metal core located therein to form the casting with a bore in its end opposite to the filling opening, the said core being substantially cylindrical, and the mold members each being formed with an enlarged counterbore into which said core projects, and the core stopping short of the end of said counterbore, whereby the mold members and core form a cavity for a cylindrical cup-shaped member, one of said mold members being formed with a transversely extending bore and a core mounted

in said latter bore and movable into engagement with the first-mentioned core to form the cup-shaped casting, with a lateral aperture, said latter core being formed with a partially cylindrical end surface for engaging the first-mentioned core and having a pair of grooves in said end surface whereby the aperture has a pair of transverse bars extending across it.

8. In a mold for casting metals, the combination of a supporting plate with a frame carried by said plate about a filling aperture in the plate, said frame having a pair of vertically aligned apertures at one end and a pair of aligned slots at the other end, a pair of mold members, each having on its inner side a portion of a cavity for the casting, one of said mold members having trunnions mounted in said pair of apertures, and the other of said mold members having guides mounted in said slots, actuating means for causing one of said mold members to slide, the other of said mold members being pivotally mounted to move its cavity side away from said plate, a supporting frame carried by the pivoted mold member, force multiplying means comprising a screw mounted on said frame, and a core connected to said screw extending longitudinally into said cavities to be retracted by said force multiplying means, means for holding

said mold members in engagement with each other about said core, and a pair of additional cores, one being mounted in each mold member for engagement with the first-mentioned core, and means for retracting the additional core members.

CARL WESSEL.
